GASOLINE LINE LOCK FOR AUTOMOBILES

Jesse E. Swayzee, Columbia, La.

Application December 29, 1931, Serial No. 583,784

Renewed November 23, 1933

4 Claims. (Cl. 70—90)

This invention relates to a gasoline line lock for automobiles and it comprises a casing surrounding and enclosing a manually operable cut-off valve in the gasoline feed line of an automobile, the casing being composed of two or more interlocked sections, levers connecting the valve with an actuating knob located outside the casing, and a slotted pin or bolt passing through the sections of the casing to lock them together and retained against unauthorized removal by a tongue formed on one of the valve actuating levers extending into the slot in such bolt, together with a lock for the valve operating levers actuated from a point externally of the casing to hold the said levers in open or closed position of the valve, the knob serving as a limit stop in one direction of movement of the levers, and one of such levers being provided with a shouldered shank serving as a limit stop in the opposite direction of movement, all as will be described more specifically hereinafter, and as claimed.

Automobiles of practically all makes are provided with a manually operated valve in the gasoline feed line, which may be closed to guard against theft of the car in the event the ignition lock is broken or short circuited by the thief.

Such gasoline line valves are not protected against tampering by unauthorized persons, however, and can only impede the prospective thief for so long a time as it requires to locate the valve. Because of this inadequate protection to the car owner, and for the further reason that, in the case of most cars, the operator must raise the hood and perhaps soil his clothes with grease and grime from the engine whenever the valve is actuated to close the gasoline line, the average car owner does not and will not avail himself of the slight protection which the commonly known unenclosed valve might afford.

It is an object of my invention to provide means, operable from the driver's seat of an automobile, for opening and closing the gasoline line valve which may be located under the hood of the car, and for positively locking the valve actuating means in either the open or closed position of the valve.

A further object is to provide a casing for the gasoline line valve of an automobile, which casing is made up of sections so fastened together that they can only be disassembled for access to the valve from the interior, and by the further provision of a lock which serves the dual function of holding the valve in open or closed position, and also of preventing unauthorized removal of the pin or key which interlocks the sec-

tions of casing together, thereby preventing unauthorized access to the valve by disassembling the casing.

A still further object of my invention is to provide a casing for enclosing the gasoline line valve of an automobile, the casing being composed of sections fastened together from the interior thereof, of means outside the casing for actuating the valve, and holding means carried by the actuating means for locking the sections of casing against unauthorized access to its interior for actuation of the valve, together with a lock controlled from a point exterior of the casing for holding the valve actuating means, either in open or closed position of the valve.

Other and further objects will be apparent from the following description and drawings, wherein:

Figure 1 is a view of the instrument board of an automobile with my invention attached thereto, showing its location in a position accessible to the driver.

Figure 2 is a view, partly in vertical section, of one form of my invention, in the position of its use.

Figure 3 is a view partly in section, taken along the line 3—3 of Figure 2.

Figure 4 is a vertical section taken along the line 4—4 of Figure 2.

Figure 5 is a horizontal sectional view along the line 5—5 of Figure 2.

Figure 6 is a modified form of my invention, partly in section, showing its application where a straight, tubular casing may be used.

Referring more particularly to the drawings:

As shown in Figure 2, a body portion 10, preferably of tubular shape, is formed with inwardly projecting ears 11 adjacent its lower opened end, and is closed by plate 12 which rests upon such ears, and is retained thereon by bolts 13 provided with nuts 14 interior of the body portion, thereby to prevent removal of the plate except when access is had to the interior of the casing.

Pipes 15 and 16 enter the walls of the body portion and are threadedly received in the body 10 of a valve 17 located within the casing. Nuts and lock nuts 18 threaded upon the pipes 15 and 16 will prevent disconnection of the pipes from the valve, except by manipulation from within the casing, and in order to provide a bearing surface for such nuts, the casing is diametrically indented to provide flat surfaces 19 and 20.

An elbow 21 is bolted to the body 10, the nuts being presented to the interior of the casing, as

shown in Figure 2, and a pivot post 22 is retained in such elbow portion, as shown more specifically in Figure 3.

The pivot post 22 is composed of sections 23 and 24, which are bolted together as at 25 and 26, for facility of assembling within the elbow, and such post carries a bell crank lever 27 which has arms pivotally connecting with link 28 and lever 29, respectively. Link 28 is pivoted to the arm 30 extending from the stem of valve 17.

A cap or casing section 31 has a peripheral flange 32 which is telescopically received within the open end of elbow 21, and which has openings adapted to register with similar openings in the elbow for the reception of a locking pin 33. This pin preferably has the form of a headed bolt which is threadedly received in the elbow at 34 (Figure 2) but it is to be understood that a threadless locking pin may be used instead.

20 The bolt 33 has a slot 34' formed in its shank, and into such slot there is adapted to extend a tongue 35 formed on or attached to the lever 29. Thus, within the normal reciprocation of lever 29, to open and close the valve, the tongue 35 will 25 ride in the slot of such bolt and will prevent removal of the bolt thereby to maintain the casing locked against unauthorized access. As will be hereinafter explained, however, it is possible for the owner of the automobile to remove the 30 tongue from engagement with the bolt, and thereby to permit access to the valve and operating mechanism thereof, for repair or other purposes.

Any suitable closure for the open end of the 35 section 31 may be used, but as shown in Figure 2, it is preferably flanged as at 36 for attachment to the instrument board of an automobile, as by means of bolts 38, and is provided with a closure plate 36', the opening in the instrument board being closed by a face plate 39. At the point where lever 29 extends through the plate 39 of the instrument board it is made of reduced diameter to define a shoulder 40 (Figure 3) which is adapted to abut a guard plate 41 45 attached to plate 39, thereby normally to prevent outward movement of the lever 29 to a point where the tongue 35 will ride out of the slot 34' in bolt 33. A head or knob 42 on the end of lever 29 serves as a limiting stop upon inward 50 movement of the lever 29.

Within this section or cap 31 the lever 29 is notched as at 43 and 44, and the sliding bolt 45 of the lock is adapted to engage in either of such notches to lock the lever in the open 55 or closed position of the valve. The lock 46 is mounted on the plate 47 carried by the cap 31 and is retained by bolts 48, such plate having an opening 49 therein, through which the lever 29 extends, and of sufficient dimension to permit 60 withdrawal of its attached tongue 35 when the casing is disassembled.

A convenient method of mounting plate 47 is shown in Figures 2 and 4 wherein the section 31 is formed with spaced inwardly extending lugs, 65 the plate 47 being provided with similarly shaped notches whereby the plate can be moved beyond the lugs in the assembly of the structure, and thereafter turned so that the lugs and notches are out of register, in which position the bolts 48 70 will extend through the openings provided in plate 36'.

The lock 46 has a barrel 50 which extends through the face plate 39 and terminates in a combination dial or key slot.

75 In the form of invention shown in Figure 6, it

is unnecessary to provide a bell crank lever, and I have, therefore, shown the lever 29 connected directly to the arm 30 of the valve. In other respects, the structure is identical to that previously described.

In the use of the assembled structure, with the valve open, in the position shown in Figure 2, when it is desired to leave the automobile unattended, the owner first unlocks the lever 29 by manipulation of the dial and withdrawal of the bolt 45 from the notch 43. Thereupon by pushing in on the knob 42, the valve is closed and the feed of gasoline is disrupted. In this position the lock is actuated so that the bolt 45 engages in notch 44, thereby locking the valve actuating lever 29 and preventing unauthorized use of the car.

80 When it is again desired to operate the automobile, the lock is actuated to release lever 29, which is then pulled outwardly until shoulder 40 abuts the guard 41, and the lock is again actuated to hold the lever in the open position of the valve. It will thus be seen that, in both the open and closed positions of the valve, the tongue 35 engages the bolt 33 to prevent its removal, and 85 consequently to prevent any disassembling of the casing which is necessary for access to the valve controlling mechanism.

90 If it should be desired to replace or repair the valve, the owner need only to remove guard plate 41 and release the lock, whereby lever 29 can be withdrawn through the face plate 39 on the instrument board to an extent which will cause disengagement of the tongue 35 from the slot in bolt 33. The bolt or pin 33 can thereupon be 95 withdrawn and the casing sections 31 and 10 separated, after which they may be separately 100 disassembled and ready access had to the valve.

95 While I have disclosed this invention as pertaining only to the protection of the valves in gasoline feed lines of automobiles, it is to be understood that it is not confined to that use alone, but may be utilized in any situation requiring the encasing of a valve to prevent unauthorized actuation, yet permitting of its actuation 110 without removal of the casing by authorized persons.

100 What I claim as my invention is:

1. In combination with a gasoline feed line, a valve therein, a casing surrounding and enclosing 105 said valve, said casing comprising telescoping sections, having registering openings therein, a slotted pin insertible in such registering openings to lock the sections of casing together, a valve actuating lever extending through the casing 110 from a point exterior of it and connected to said valve, a projection carried by said lever and engageable in the slot of said pin in the normal action of opening and closing the valve, whereby the pin cannot be withdrawn and the casing can 115 not be disassembled for access to the valve, means comprising shoulders on said lever for normally abutting a fixed stop to limit movement of said lever and locking means for maintaining said lever in the open or closed position of the valve. 120

2. In combination with the gasoline line of an automobile, a manually operable valve in said line, a casing surrounding and enclosing said valve, said casing comprising a plurality of telescoping sections, a slotted pin received through 125 the telescoped ends of said sections, the outermost of such sections extending into the driver's compartment of an automobile, a lever extending from a point exterior of the casing into it and connected to operate the valve, said lever hav- 130

ing an offset tongue received in the slot of said pin to prevent unauthorized removal of the pin, said lever further being notched at spaced points to receive the bolt of a lock mounted within the 5 casing, and actuated from the exterior thereof for locking the valve in open or closed position, said lever having a reduced portion defining spaced shoulders, a face plate through which said reduced portion of the lever passes, the 10 shoulders serving as limit stops to prevent removal of the tongue from the slot in the said pin, and thereby to prevent unauthorized disassembly of the casing for access to the valve.

3. A valve casing comprising a body portion 15 surrounding a valve, inlet and outlet pipes extending through said body portion and threaded into said valve, nuts and lock nuts between the wall of the body portion and the respective ends of the valve, said body portion being flattened adjacent the points at which the inlet and outlet 20 pipes enter to constitute bearing portions for the lock nuts.

4. A valve casing comprising a body portion surrounding and enclosing a manually operable 25 valve, ears extending inwardly from the interior surfaces of said body portion against which a bottom plate is retained by bolts, nuts on said

bolts interior of the body portion for preventing removal of said plate from the outside, an arm on the stem of said valve, a lever pivoted to said arm and extending through said casing, an offset tongue on the lever, a cap constituting a part of the casing in the assembled structure, said cap having a peripheral flange telescopically associated with the outer end of the body portion, the telescoping ends of the cap and body portion being provided with registering openings, a fastening pin extending through such registering openings and having a slot in its shank, through which said tongue extends, to prevent removal of said pin and consequent disassembly of the casing for access to the valve, the outer end of the lever extending through said cap and having a reduced portion defining spaced shoulders for limiting reciprocation of the lever to open and close the valve without releasing the said tongue from the slot in said fastening pin, a guard plate surrounding said reduced portion of the lever, attached to a fixed support and serving as an abutment for the spaced shoulders on the lever, and a lock carried by said casing engageable with the said lever to hold it in either the open or 100 closed position of the valve.
